UNITED STATES PATENT OFFICE.

ARTHUR J. FREEMAN, OF ALAMEDA, CALIFORNIA.

SHEET CONVEYER.

Application filed March 18, 1924. Serial No. 700,068.

This invention relates to improvements in sheet conveyers and particularly pertains to apparatus for carrying sheet material through chemical solutions or liquids.

5 It is the object of this invention to provide a machine, particularly adapted to photographic work, which embodies means for carrying sheets of material through several chemical solutions and water, submitt-
10 ting the sheets to the successive action of various chemical solutions for a predetermined length of time and automatically discharging the sheets from the machine.

A further object is to provide in a ma-
15 chine of the above character, an endless sheet conveyer having numerous consecutive sheet holders, to which at regular intervals, sheets may be fed successively and continuously.

Another object is to provide a simple and
20 efficient means for increasing the speed of travel of a sheet during the time it is being delivered to and withdrawn from a chemical solution and to control the relative length of time that a sheet remains in the various
25 solutions.

Another object is to supply simple means for temporarily isolating a sheet holder to facilitate the loading of sheets into the holders, the transferring of sheets from one tank
30 to another and the discharging of the sheets from the machine.

The invention further consists of the parts and the construction and combination of parts, as hereinafter more fully described
35 and claimed, having reference to the accompanying drawings, in which—

Figure 1 is a plan view of the invention with parts broken away, showing a sheet holder in position to receive a sheet, and other sheet holders, transferring sheets from one tank to another, carrying sheets through the several tanks, draining sheets, and discharging sheets from the machine. Fig. 2 is a front elevation of the machine, part in section on line 2—2 of Fig. 1. Fig. 3 is a detail section of a sheet holder and the sheet discharging mechanism. Fig. 4 is a side view in diagram of the solution tanks. Fig. 5 is an enlarged detail of a carrier 15. Fig. 6 is a section of one of the drive sprockets.

In the drawings, A represents a frame in which the various parts of my invention are mounted, this frame being disposed in substantially a horizontal position as is here illustrated. Situated adjacent to and around the frame A at various levels is a series of tanks 1—2—3—4—5—6, adapted to hold various chemical solutions or water, particularly shown in diagram Fig. 4.

Mounted in suitable bearings on the frame A are the sprockets 7 8 9 10 11, designed with grooved teeth, as shown in Fig. 6 and adapted to carry and drive an endless flexible cable 12. The sprockets 7 and 8 are mounted on the top side of frame A and the sprockets 10 and 11 on the underside while the sprocket 9 is mounted at the outer end and on a horizontal plane half way between the sprockets 8 and 11. The sprockets 7 and 10 drive the cable 12 and are keyed to the shaft 13 and continuously rotated through a pulley 14 from any source of power. The sprockets 8 9 11 are idlers and are designed to carry and guide the cable 12 in its prescribed course. The sprockets are all 75 designed with few teeth and a large pitch compared with their diameter, the purpose of which will be described later herein.

The cable 12 extends completely around the frame A and is designed to continuously 80 travel on a helical-like course about the frame. Beginning at sprocket 7 the cable 12 extends horizontally across to and part way around sprocket 8, thence running at a slight angle downward to and approximately half way around sprocket 9, continues at a downward angle to and part way around sprocket 10, completing one helical like turn, it then extends horizontally across to and halfway around sprocket 11, then passing 90 under guide roller 27 runs upward at an angle to and over guide roller 28 and back to sprocket 7 and the starting point, making a complete circuit. The path of cable 12 is here illustrated as making one helical like turn 95 and returning to the starting point but it may consist of a number of helical or volute like turns and then return to the starting point to make a complete circuit, the object of using a number of turns would be to in- 100

crease the capacity of the machine without increasing the floor-space occupied thereby. The cable 12 is here illustrated as constructed of flexible material such as strand-
5 ed steel but it may be a linked chain.

Mounted on cable 12 at regular intervals throughout its entire length are the sheet carriers 15, formed with side members 15' through which the cable 12 passes, the holes 10 therein being slightly larger than the cable. The carriers 15 with the arm members 16 and sheet clips 17 are free to turn about the cable but have their longitudinal position fixed thereon by the collars 18 which 15 are adapted to fit between the members 15' and be securely fastened to the cable as shown in Fig. 5. The clips 17 are formed in the shape of a U having two angular sides, the outer ends of which carry the overlapping 20 jaws 23, and the spring tension of which normally exerts an outward pressure and holds the jaws closed to retain a sheet of material. The jaws may be opened by exerting an inward pressure on the two sides 25 of the clip. The dimensions of carriers 15, and their spacing on cable 12, is designed to correspond with the pitch of sprockets 7 8 9 10 11 and enables them to serve as driving blocks for the cable. The carrier 30 arms 16 are maintained in an approximately horizontal position by the rail 19 on which they ride and which extends approximately parallel to the cable 12 throughout the entire course. The outer ends of arms 16 carrying 35 sheet clips 17 extend into the tanks 1 2 3 4 5 6 and serve to carry sheets of material held in the clips through various solutions that may be contained in the several tanks. The cable 12 follows the contour of 40 the tanks in general but the track 19 and arms 16 follow the contour accurately, the weight of clips 17 holding the arms 16 against the track 19 at all points. The sheet clips 17 are free to turn about the arms 45 16 but have their longitudinal position fixed thereon by nuts 20. The clips 17 are constructed of spring material and are designed to receive and hold sheets of material by gripping them near the edge and 50 may be opened to release a sheet by pressing on either side as shown in Fig. 3. The clips 17 normally hang in a perpendicular position but when loaded with sheets and while being dragged through solutions in 55 the tanks assume a slight angle as shown in Fig. 2, and when passing from one tank to another may be lifted to a horizontal position. The clips 17 normally travel in a straight course but when they reach a sprocket their course of travel changes from 60 a straight line to an arc and due to the comparatively large radius of their arcuate path their speed of travel is considerably increased. The entrances to and the exits 65 from certain tanks are placed at these points

to take advantage of this increase of speed to quickly deliver to and from the tanks. During the time the clips are traveling in this circular course they are widely separated, this facilitates the attaching of 70 sheets to the clips and permits the delivery of the sheets to and from certain tanks one at a time without disturbing the preceding or succeeding sheets and also permits the discharge of the sheets one at a time onto 75 the traveling belt 25 and allows time for the belt to carry the discharged sheet from the machine before another reaches the discharge point. Due to the manner in which the carriers 15 are mounted on the cable 80 12 any clip and sheet may be withdrawn from the tanks at any point and separated from the preceding and succeeding clips and sheets for observation or removal by lifting the clips and turning the carrier 15 about the cable 12. This feature of the invention permits the carriers 15 to be compactly arranged and closely spaced on cable 85 12 to reduce the dimensions of the machine.

Mounted on the underside of tank 2, and directly opposite the sprocket 11, is the sheet discharging mechanism consisting of the rollers 21 and 22 which are mounted one above the other and accurately spaced apart to permit the clips 17 to pass through 90 but slightly pressing the sides together and opening the jaws 23 releasing a sheet 24 held therein and dropping it onto a traveling belt 25 running over a pulley 26 as shown in Fig. 3.

In operation the shaft 13 is constantly rotated through the pulley 14 from any source of power so as to transmit constant traveling motion to the cable 12 through 95 the drive sprockets 7 and 10.

Assume the parts to be in the position shown in Figures 1 and 2 in which the sheet carrier 15 is about to enter tank 1 and is in position to be loaded with a sheet of material while the preceding carrier has 100 just entered the tank 1, others are passing through the tank, and one having reached the sprocket 8 is rapidly transferring a sheet from the tank 1 to the tank 2, while other carriers are conveying sheets through 110 the tanks 3 4 5 6. After a carrier leaves the tank 6 it travels for a distance under the tank 1 and outside of any tank, the purpose here being to allow the surplus solutions or water to drain from the sheet and clip, after which it reaches the sprocket 11 and is carried through the discharge rollers 21 22 which press the sides of the clip and release the sheet held therein dropping it 120 onto the belt 25 which is continuously in motion and carries the sheet from the machine.

While my invention may be used for a number of purposes it is suited perfectly for the development, fixing and washing of 125 130

photographic sheet prints and for this purpose tank 1 may contain a developing solution and tank 2 an acid rinse water while tank 3 or tanks 3 and 4 may contain a hypo fixing bath and tanks 5 and 6 other chemicals or wash water. For this purpose an exposed sheet of photographic paper may be attached to a clip, while in motion, just before it enters the tank 1 and it will be quickly immersed and then carried through the developing solution contained in the tank, then quickly transferred to tank 2 containing rinse water and from there carried into a hypo fixing solution contained in tanks 3 and 4 and then through a wash water contained in tanks 5 and 6 and after leaving tank 6 the surplus water will be allowed to drain from the print while it passes under tank 1 and it will be discharged from the machine onto a traveling belt 25 which may be canvas or other suitable material on which to dry photo prints. The length of time during which the prints are being carried through the various tanks may be controlled by either altering the lengths of the tanks or by varying the speed of the pulley 14.

From the foregoing it will be seen that I have provided a sheet conveyer which may be operated continuously and to which sheets of material may be fed and which will carry the sheets into and through various solutions, drain the surplus solution from the sheets and discharge the sheets from the machine.

35. I claim:

1. In a sheet conveyer a plurality of sheet holders, means for connecting said holders to form a chain, means for temporarily isolating a sheet holder to facilitate the attaching of a sheet thereto and the discharging of a sheet therefrom, mechanism for carrying and driving said chain of holders to convey sheets of material and means for discharging the sheets from the holders.

45. 2. A sheet conveyer comprising a plurality of sheet holders, means for connecting said sheet holders to form a chain, mechanism for carrying and driving said chain of holders through a series of tanks, whereby sheets of material carried by said holders will be submitted to the action of the contents of said tanks and means for temporarily isolating and increasing the speed of travel of a sheet holder during the time it is entering a tank, leaving a tank and discharging a sheet.

60. 3. In a sheet conveyer a train of sheet holders, means for carrying and driving said train over a course to receive and convey sheet material, means for temporarily increasing the speed of travel of a sheet holder while traveling over certain portions of said course, means for mounting the sheet holders whereby a sheet holder may be isolated from the train at any point on said

course and mechanism for discharging the sheets from the holders.

4. In a sheet conveyer a train comprising a plurality of closely assembled sheet holders, means for carrying and driving said train on a course adjacent a series of tanks whereby sheets of material carried by said holders will be submitted to the action of the contents of said tanks, means for increasing the distance between a holder and its preceding and succeeding holders during the time it is entering a tank, leaving a tank and discharging a sheet.

5. A sheet conveyer comprising a train of closely assembled sheet holders, means for temporarily increasing the space between a sheet holder and its preceding and succeeding holders, means for carrying, guiding and driving said train on a course adjacent a series of tanks whereby sheets carried by said train will be submitted to the actions of the contents of said tanks, means for changing the speed at which a holder travels while it is traveling over certain portions of said course, means for controlling the relative lengths of time that a sheet is subject to the actions of the contents of the tanks.

6. A sheet conveyer comprising a train of sheet holders, means for carrying and driving said train on a circuitous course adjacent a series of tanks so that sheets carried in said holders will be conveyed to, through and from the tanks, means for transferring sheets from one tank into another, means for controlling the relative lengths of time that a sheet remains in the different tanks of the series, means for increasing the speed of travel of a sheet holder while it is traveling over certain portions of said course without increasing the general speed of the train over other portions of the course and means for the continuous successive delivery of sheets to and from the tanks.

7. A sheet conveyer comprising a plurality of closely assembled sheet holders, means for carrying and driving said holders over a circuitous course having both straight and arcular sections adjacent a series of tanks, so that sheets of material carried by said holders will be submitted to the actions of the contents of the tanks, means for isolating and increasing the speed of travel of a sheet holder as it approaches and enters a tank then reducing its speed and reassembling it with the other holders while it is passing through the tank and again increasing its speed of travel and isolating it as it leaves the tank, so as to quickly immerse a sheet in the contents of a tank, allow the sheet to remain in the tank for a time and then quickly withdraw the sheet from the tank, means for isolating a sheet holder to discharge a sheet, means to discharge the

- sheet and means for effecting the continuous successive travel and operation of the sheet holders over the said course.
8. A sheet conveyer comprising a train 5 of closely assembled sheet holders mounted on a common carrier, means for guiding and driving said carrier and train on a course adjacent a series of tanks whereby sheets of material carried by said holders 10 will be submitted to the actions of the contents of said tanks, means for mounting said holders whereby a holder may be isolated from the train at any point on said course to allow the attaching of a sheet thereto or the detaching of a sheet therefrom or the examination of a sheet held thereby or the removal of a sheet from the tanks.
9. A sheet conveyer comprising a train 20 of closely assembled sheet holders, means for carrying and driving said train on a course through a series of tanks, means for increasing the speed of travel of a sheet holder while it is entering a tank and leaving a tank without increasing the general speed of the train over the other sections of the course, and means for isolating a sheet holder from the train to receive or discharge sheets.
10. The combination of a train of sheet carriers having projecting arm members, sheet holders on said arms, means for mounting said train to travel a continuous course, means for driving the train and operating the sheet holders to hold, convey and discharge sheet material and means for temporarily isolating a sheet holder to load and discharge sheets.
11. In a sheet conveyer a train of sheet 40 holders, means for carrying and driving said train on a course adjacent a series of tanks whereby sheets of material carried by said holders will be submitted to the actions of the contents of said tanks, means for temporarily increasing the distance between a holder and its preceding and succeeding holders and increasing its speed of travel during the time it is entering a tank, leaving a tank and discharging a sheet.
12. In a sheet conveyer a plurality of sheet 50 holders connected in chain like formation, means for carrying and driving said holders over a continuous spiral-like course and adjacent a series of tanks whereby sheets carried by the holders will be submitted to the actions of the contents of said tanks and means for temporarily isolating a sheet holder to permit the attaching of a sheet thereto and the discharging of a sheet therefrom.
13. A sheet conveyer comprising a plurality 60 of closely assembled sheet holders connected in train like formation, means for carrying and driving said holders through a series of tanks, means for isolat-

ing and increasing the speed of travel of a sheet holder as it enters a tank then reducing its speed and reassembling it with the other holders while it is passing through the major portion of the tank and again 70 isolating it and increasing its speed of travel as it leaves the tank, so as to quickly immerse a sheet in the contents of a tank then allow the sheet to remain in the tank for a period of time then quickly withdraw 75 it from the tank.

14. In a sheet conveyer a plurality of sheet holders closely assembled and mounted in train-like formation on an endless common carrier, means for driving said train 80 over a circuitous course adjacent a series of tanks whereby sheets of material carried by said holders will be submitted to the actions of the contents of said tanks, means for temporarily increasing the space between a sheet holder and its preceding and succeeding holders at certain points on said course to facilitate the loading and discharging of sheets and to isolate a sheet carried by said holder, means for mounting 85 said sheet holders whereby a sheet holder may be isolated from the train at any point on said course to facilitate the attaching of a sheet or the detaching of a sheet or the examination of a sheet held therein, means for increasing the speed of travel of a sheet 90 holder over certain portions of said course without increasing the general speed of the train over other portions of the course, means for controlling the relative lengths 100 of time that a sheet holder remains in the different tanks of the series, means whereby the sheets in said holders may be maintained in either a horizontal, perpendicular or oblique position, means to discharge the 105 sheets from the holders and means for effecting the continuous successive travel and operation of the sheet holders over the said course to convey sheet material.

15. A sheet holder comprising a train of 110 sheet holders, a course for said train having both straight and arcular sections adjacent a series of tanks, means for operating the train over said course so as to carry sheets held in said holders toward and through 115 the tanks and from one tank to another, an arcular section of said course adjacent the entrance of a tank to facilitate the delivery of a sheet to the tank.

16. The combination of an endless conveyer having a train of closely assembled sheet carriers projecting laterally therefrom and pivotally mounted thereon so as to have arcuate movement about said conveyer whereby a carrier may be temporarily isolated from the train, sheet grippers on said carriers, and means for driving the conveyer and operating the grippers to continuously and successively receive, convey 125 and discharge sheet material.

17. In a machine of the character described, an automatic means for isolating and conveying the sheets to be treated toward and immersing them in a treating solution, then transferring them successively to and from other solutions for further treatment including lastly a washing bath, then draining the washing bath from the sheets, and then discharging the sheets from the machine, and driving mechanism for effecting the several operations continuously and successively.
- 5 In testimony whereof I have hereunto set my hand.

ARTHUR J. FREEMAN.
